Primary Examiner—Celia Murphy
Attorney, Agent, or Firm—Bernhard Kreten[57] **CLAIM**

The ornamental design for a sole for a golf shoe, as shown and described.

DESCRIPTION

FIG. 1 is a perspective view of a sole for a golf show showing my new design.
 FIG. 2 is a left side view thereof;
 FIG. 3 is a bottom view thereof;
 FIG. 4 is a right side view thereof;
 FIG. 5 is a top view thereof;
 FIG. 6 is a front view thereof;
 FIG. 7 is a rear view thereof; and,
 FIG. 8 is a sectional view taken on line 8—8 of FIG. 3. The broken-line showing of environmental structure in FIGS. 1, 2, 4 and 6 through 8 are for illustrative purposes only and form no part of the claimed design.
